(57) **CLAIM**

The ornamental design for a counterweight for a lift truck, as shown and described.

DESCRIPTION

FIG. 1 is a perspective view of the counterweight for a lift truck;

FIG. 2 is a rear elevational view thereof;

FIG. 3 is a front elevational view thereof;

FIG. 4 is a left elevational view thereof; and

FIG. 5 is a right elevational view thereof;

FIG. 6 is a top view thereof; and,

FIG. 7 is a bottom view thereof.

The broken lines in the drawings are included for the purpose of illustrating portions of the counterweight for a lift truck and form no part of the claimed design.
